UNITED STATES PATENT OFFICE.

CHARLES W. BECK, OF ROCKVILLE CENTER, NEW YORK, ASSIGNOR, BY MESNE ASSIGNMENTS, TO BECK-FROST CORPORATION, OF DETROIT, MICHIGAN, A CORPORATION OF MICHIGAN.

SPARK-PLUG.

1,136,996.

Specification of Letters Patent. Patented Apr. 27, 1915.

Application filed February 18, 1910. Serial No. 544,570.

To all whom it may concern:

Be it known that I, CHARLES W. BECK, a citizen of the United States, and resident of Rockville Center, county of Nassau, and State of New York, have invented certain new and useful Improvements in Spark-Plugs, of which the following is a specification, reference being had therein to the accompanying drawings, in which—

10 Figure 1 is a longitudinal central section of the base of the plug, the inner porcelain part being shown partly in side elevation; Fig. 2 a perspective view of the removable split thimble; Fig. 3 a view similar to Fig. 15 1 showing my invention applied to a spark plug of an ordinary well-known construction; Fig. 4 a side elevation of the plug shown in Fig. 1; and Fig. 5 a detail view partly in section of the inner end of the insulator or porcelain part of the plug.

20 In spark plugs of the ordinary construction, the firing wire, the inner end of the spark plug casing or base, and the inner end of the porcelain part or insulated electrode become so coated with soot that the current will find its way from one electrode to the other through the accumulated soot. Of course, when this occurs the plug is inoperative and must be removed and thoroughly 25 cleaned. This cleaning is a disagreeable and difficult operation.

It is one of the principal objects of my invention to provide a spark plug with means by which the accumulated soot may 30 be readily removed from the plug, said means consisting of a removable thimble or sleeve adapted to be fitted within the spark plug casing or base and on which the soot will accumulate so that by removing said 35 thimble the soot will be removed with it.

40 It may be readily cleaned and replaced, or if desired, a clean thimble may be immediately inserted in the plug casing, the old coated thimble being set aside to be cleaned 45 when convenient.

Another object of the invention is to provide a porcelain or insulated electrode with a removable section or covering on which the soot will be deposited, and which may 50 be readily removed and cleaned, or a fresh section or covering put in place, the old one being set aside to be cleaned at leisure.

Another object of the invention is to provide a removable firing wire to be connected

to the electrode carried by the insulator or porcelain part of the plug, said firing wire extending outwardly to the rim of the split sleeve so that the spark will jump from said firing wire to the sleeve or to the engine cylinder. This removable firing wire also 60 serves as means for securing the removable section or cover on the insulator.

A further object of the invention is to simplify, and therefore cheapen, the construction of the metal parts of the plug 65 which constitute the base.

Referring to the various parts by numerals, 1 designates the side of the engine cylinder and 2 the spark plug screwed therein. I preferably form the base of the 70 plug in two parts, 3 and 4, the part 3 being cylindrical and threaded exteriorly throughout its length; the part 4 being chambered on its inner end and interiorly threaded to receive the outer end of the part 75 3. The part 4 is formed with the usual hexagonal nut by which the plug is screwed in the engine cylinder. The inner end of the cylindrical part 3 is formed at diametrical points with the slots 5 in which may be engaged a suitable wrench by means of which the two parts of the plug may be screwed together. I form the base of the plug in two sections in order to cheapen the manufacture of the device; and in assembling the 80 85 two parts they are screwed together in such manner that the ordinary operation of securing the plug into the engine cylinder and unscrewing it therefrom will not disconnect said parts. It will, of course, be understood, 90 however, that the two parts may be separated by applying an unusual pressure thereto tending to unscrew the nut part from the cylindrical part.

The cylindrical part 3 of the base is 95 formed near its outer end with an interior annular flange 6, the outer surface of which forms a shoulder 7 against which the inner edge of the enlarged part 8 of the insulator 9 rests. The nut portion 4 is formed with 100 an interior chamber 10 which is adapted to receive the outer portion of the enlargement 8 of the insulator and between the outer end of said enlargement and the part 4 of the nut is placed a suitable packing ring 11 to 105 prevent the escape of gases. A packing gasket 12 is also placed between the inner end of the nut portion and the engine cylinder to

provide a yielding seat for the inner edge of the said nut portion. In the ordinary construction of spark plugs a firing wire is connected to the inner end of the base part 5 of the plug. I dispense with this firing wire and insert in said cylindrical portion a split metal sleeve 13, said sleeve normally being slightly larger in diameter than the interior of the said cylindrical part of the plug casing so that it may be forced into said casing and held therein by friction. This sleeve covers the interior of the cylinder 3 and protects it, the soot being deposited on the interior of said sleeve instead of on the 10 plug base. This sleeve is formed at its inner end with a flange 14 which extends outwardly over and covers the inner edge of the plug casing. This flange, of course, is slightly smaller in diameter than the cylindrical part 3 of the casing so that it may be 15 readily withdrawn with the spark plug through the threaded opening in the cylinder side.

On the electrode 15 of the insulator 9 is 20 screwed, or otherwise detachably secured, a firing wire 16 which extends outwardly from said electrode and over-lies the flange 14 of the split sleeve so that the spark will jump from said firing wire to the sleeve flange or to the engine cylinder. An insulator 9 is shown in Fig. 1 as reduced at its 25 lower end to form the stem 17 through which the electrode 15 extends. Fitting this stem is a removable section 18 preferably formed of porcelain or other suitable insulating material. A washer 19 is preferably interposed between the body of the insulator and the upper end of the removable section 18 so that said removable section 30 may be securely clamped in place by the firing wire without danger of breaking the said section. By forming the inner end of the insulator in two telescoping parts, said 35 parts serve as a double insulator and remove any possibility of a leak from the electrode through the insulator.

In Fig. 5 the insulator is shown with a removable section 20, an insulating washer 21 being interposed between the body of the insulator and the removable portion in order to prevent any sparking or leakage of current at the joints between the two sections, and also permitting the removable section to be firmly clamped by means of the firing wire.

In Fig. 3 I have shown the removable split sleeve and a removable insulator section applied to a spark plug of ordinary construction, the removable insulator section being shown in the form of a cap or cover 17. The firing wire is also shown as screwed to the end of the electrode carried by the insulator and serving as means for holding the said removable section or cover 40 in place.

From the foregoing it will be readily understood that to thoroughly clean the plug it will only be necessary to detach the split sleeve and the section or covering of the porcelain. These two parts may then be 45 cleaned, or if desired, a clean sleeve and a clean section or covering for the insulator may be replaced in the plug. The soot-covered parts may be either discarded entirely or laid aside to be cleaned at a convenient 50 time. By providing this means for cleaning that end of the plug subject to the engine cylinder gases, the base of the plug may be made in two parts as shown, and said two parts practically permanently secured together to retain the insulator therein as it will not be necessary to detach said insulator from the base in order to clean it. This is desirable for the reason that when the packing gasket 11 is compressed to form 55 a gas-tight joint, it is of advantage to permit it to remain undisturbed. In the ordinary form of spark plug the insulator must be frequently removed in order to clean it, and each removal requires that the gas retaining gasket must be recompressed, thereby shortening the life of the packing and rendering it more and more difficult to retain a gas-tight joint. The porcelain is frequently 60 broken when securing it in place in the base.

It will, therefore, be seen that I provide a spark plug of simple and cheap construction which may be readily cleaned.

I desire it understood that the insulator 65 may be made of porcelain or any other insulating material. The sleeve 13 may be made of any suitable material.

Having thus fully described my invention, what I claim as new and desire to secure by Letters Patent is:

1. A spark plug comprising a tubular base, an insulator supported by said base and carrying an electrode, said insulator extending through the base and the inner end thereof being smaller in diameter than the interior of the inner portion of the base whereby a gas space of considerable capacity is formed within the base and around the inner part of the insulator, and removable protectors for the inner end of the base and the inner end of the insulator, said protectors serving as means to prevent the deposit of carbon on the inner surface of the base and the exterior of the insulator.

2. A spark plug comprising a tubular base, an insulator supported by said base and carrying an electrode, said insulator extending through the base and the inner end thereof being smaller in diameter than the interior of the inner portion of the base, and removable protectors for the inner end of the base and the inner end of the insulator, the insulator and its protector being considerably smaller than the interior of

the base protector, whereby a gas space of considerable capacity will be formed around said insulator protector.

3. A spark plug comprising a tubular base, an insulator supported by said base and carrying an electrode, said insulator extending through the base and the inner end thereof being smaller in diameter than the interior of the inner portion of the base, and a thin removable protector for the inner end of the insulator, said protector being out of contact with the base whereby a gas space of considerable capacity will be formed between said protector and the inner surface of the base and said protector will serve as a means to prevent the deposit of carbon on the insulator.

4. A spark plug comprising a tubular base, an insulator supported by said base and carrying an electrode, said insulator extending through the base and the inner end thereof being smaller in diameter than the interior of the inner portion of the base, and a removable protector of non-conducting material covering the inner end of the insulator, said insulator and protector being smaller in diameter than the interior of the base, whereby a considerable gas space will be formed around said protector and said protector will prevent the deposit of carbon on the insulator.

5. A spark plug comprising a tubular base, an insulator supported by said base and carrying an electrode, said insulator extending through the base and the inner end thereof being smaller in diameter than the interior of the inner portion of the base, a thin removable protecting and nonconducting sheath or covering on the inner end of the insulator within the base, said insulator and sheath being considerably smaller in diameter than the interior of the base,

and a detachable firing pin carried by the electrode and serving to hold the sheath or protector in position on the insulator.

6. A spark plug comprising a tubular base, an insulator supported by said base and carrying an electrode, said insulator extending through the base and the inner end thereof being smaller in diameter than the interior of the inner portion of the base, a thin removable protecting and nonconducting sheath or covering on the inner end of the insulator within the base, said insulator and sheath being considerably smaller in diameter than the interior of the base, and a detachable firing pin carried by the electrode and serving to hold the sheath or protector in position on the insulator, and a thin removable protector of conducting material for the interior of the base.

7. A spark plug comprising a tubular base, an insulator supported by said base and carrying an electrode, said insulator extending through the base and the inner end thereof being smaller in diameter than the interior of the inner portion of the base, a thin removable protecting and nonconducting sheath or covering on the inner end of the insulator within the base, said insulator and sheath being considerably smaller in diameter than the interior of the base, a thin removable protector of conducting material for the interior of the base, and a firing pin secured to the electrode and serving as means to prevent the detachment of either one of the protectors.

In testimony whereof I hereunto affix my signature in the presence of two witnesses this 17th day of February, 1910.

CHARLES W. BECK.
